UNITED STATES PATENT OFFICE.

ALBION M. ROUSE, OF BOULDER, ASSIGNOR TO THE BOSS-GRIP LOCK-NUT COMPANY, OF DENVER, COLORADO.

DESIGN FOR A LOCK-NUT.

SPECIFICATION forming part of Design No. 22,813, dated September 26, 1893.

Application filed October 19, 1892. Serial No. 449,401. Term of patent 14 years.

To all whom it may concern:

Be it known that I, ALBION M. ROUSE, a citizen of the United States, residing at Boulder, in the county of Boulder and State of Colorado, have invented and produced a new and original Design for Lock-Nuts, of which the following is a specification, reference being had to the accompanying drawing, showing a part thereof.

10 The drawing is a perspective view, showing my design.

The leading feature of my design consists of a top having a circular rim at one end, and a conical portion at the other end.

1 is the body or central portion, at one end 15 of which is a circular rim 2, and at the other end of which is a conical portion 3, with notches 4.

1 claim as my invention—

The design for a lock nut herein shown and 20 described.

ALBION M. ROUSE.
